UNITED STATES PATENT OFFICE

94,764

DESIGN FOR A COSMETIC CONTAINER

Ellison S. Irelan, Elgin, Ill., assignor to Illinois Watch Case Company, Elgin, Ill., a corporation of Illinois

Application December 24, 1934, Serial No. 54,583

Term of patent 7 years

To all whom it may concern:

Be it known that I, Ellison S. Irelan, a citizen of the United States, residing at Elgin, in the county of Kane and State of Illinois, have invented a new, original and ornamental Design for a Cosmetic Container, of which the following is a specification, reference being had to the accompanying drawing, forming part thereof, in which—

Fig. 2 is a side elevation of a cosmetic container showing my new design.

I claim:

The ornamental design for a cosmetic container, as shown.

ELLISON S. IRELAN.
